CLAIM

The ornamental design of a combined grass collector and blower, as shown and described.

DESCRIPTION

FIG. 1 is a front perspective view of a combined grass collector and blower showing our new design;

FIG. 2 is a rear perspective view thereof;

FIG. 3 is a front elevational view thereof;

FIG. 4 is a rear elevational view thereof;

FIG. 5 is a side elevational view taken from the right of FIG. 1;

FIG. 6 is a side elevational view taken from the left of FIG. 1;

FIG. 7 is a top plan view thereof;

FIG. 8 is a bottom plan view thereof.

FIG. 1

FIG. 2
